US00D722596S

(12) **United States Design Patent**
VanDuy et al.

(10) **Patent No.:** **US D722,596 S**
(45) **Date of Patent:** **** Feb. 17, 2015**

(54) **REMOTE CONTROL**

(71) **Applicant:** **EchoStar Technologies L.L.C.**,
Englewood, CO (US)

(72) **Inventors:** **Luke VanDuy**, Highlands Ranch, CO
(US); **Henry Gregg Martch**, Parker, CO
(US)

(73) **Assignee:** **EchoStar Technologies L.L.C.**,
Englewood, CO (US)

(**) **Term:** **14 Years**

(21) **Appl. No.:** **29/459,171**

(22) **Filed:** **Jun. 26, 2013**

(51) **LOC (10) Cl.** **14-03**

(52) **U.S. Cl.**

USPC **D14/218**

(58) **Field of Classification Search**

(57) **CLAIM**

The ornamental design for a remote control, as shown and described.

DESCRIPTION

FIG. 1 is an isometric view of a remote control showing my new design;

FIG. 2 is a top plan view thereof;

FIG. 3 is a bottom plan view thereof;

FIG. 4 is a first side plan view thereof;

FIG. 5 is a second side plan view thereof;

FIG. 6 is a front view thereof; and,

FIG. 7 is a rear plan view thereof.

The broken lines in the figures depict surface indicia that form no part of the claimed design.
